UNITED STATES PATENT OFFICE.

EDWIN FITTS, OF DETROIT, MICHIGAN, ASSIGNOR TO DETROIT STOKER COMPANY, OF DETROIT, MICHIGAN, A CORPORATION OF MICHIGAN.

FURNACE.

1,158,998.

Specification of Letters Patent.

Patented Nov. 2, 1915.

Application filed August 25, 1911. Serial No. 646,077.

To all whom it may concern:

Be it known that I, EDWIN FITTS, a citizen of the United States of America, residing at Detroit, in the county of Wayne and State of Michigan, have invented certain new and useful Improvements in Furnaces, of which the following is a specification, reference being had therein to the accompanying drawings.

- 10 The invention relates to furnaces of that type in which a fuel magazine is arranged at the side, and a refractory arch forming the top of the combustion chamber is supported upon an abutment secured to said magazine. Air twyers are also provided adjacent to the abutment for the combined purpose of lowering the temperature thereof and supplying heated air to the combustion chamber.
- 15 It is one of the objects of the invention to provide an abutment which is protected from the intense heat of the furnace chamber, and a further object is to provide air twyers which are independently detachable and renewable.
- 20 With these objects in view the invention consists in the various features of construction as hereinafter set forth.

In the drawings,—Figure 1 is a sectional perspective view of a portion of the furnace embodying my improved construction; Fig. 2 is a detached perspective view of the detachable twyer member, the locking key therefor and the heat insulating member for the arch abutment; Fig. 3 is a vertical cross section of the arch and its support; and Fig. 4 is a side elevation partly in section showing the manner of detachably engaging the twyers.

40 A is a member forming the inner wall of the fuel magazine and the support for the arch abutment. This member is preferably formed of cast metal and is provided on its inner face with a plurality of inwardly extending strengthening ribs or ledges B, B', B² which in conjunction with intersecting vertically extending flanges C form a rigidly trussed structure. The refractory arch is preferably formed of an outer and an inner arch section D and E having an air chamber F therebetween, both of said sections having abutments upon the member A. As shown, the upper arch section D abuts against the plate G supported upon the inclined faces G' of the vertically extending

flanges C. The lower arch section E which is subjected to the most intense heat is also supported by the vertical flanges C, which to this end are provided with inward extensions H preferably of triangular shape. The inclined face of these extensions H are at the proper angle to receive the thrust of the arch perpendicular thereto, and to take care of the stress therein, ribs I are preferably arranged at the lower edge of this triangular section.

The extensions H are protected from the heat of the furnace chamber by refractory blocks J arranged beneath the same. These blocks J are preferably of a length to extend between adjacent vertical flanges C and are preferably supported by grooved bearings K at the opposite ends thereof, which are engaged with the ribs I on the sections H. Beneath the point of engagement the blocks J are provided with end extensions L which abut against each other. Thus when in place the blocks completely shield the abutment sections H and prevent the overheating of the same.

The air twyers are formed below the blocks J and communicate with the space on the inner side above said blocks which communicates with the chamber F between the arch sections. These twyers are preferably formed of a series of sections M of cast metal, each section comprising an inclined bottom plate N and upwardly extending ribs O, the latter extending to the lower face of the blocks J.

The sections M are supported preferably by upwardly extending hook members P which lie adjacent to the magazine wall A and engage with socket members Q thereon. The arrangement is such that the sections M may be successively placed in engagement with the member A by first moving the hooks P upward into the sockets Q and then shifting said member laterally to engage the hook with the top of the socket. The ends of the members M are preferably fashioned with overlapping flanges M' and M², sufficient clearance being provided to permit the longitudinal adjustment necessary for engagement and disengagement of the hooks P. The members M are locked from disengagement by keys R which may be dropped into grooves formed by the overlapping flanges M' and M², a head R' on each key preventing its dropping out. One of the end mem-

bers is also preferably provided with reverse turned hooks P'.

With the construction as described in first building the arch the blocks J are placed in engagement with the flanges I. The arch section E is then laid, the triangular members H forming the abutments. Or if desired, a straight bar S may be placed over these triangular members and the arch built thereon. It will be noted that the blocks J do not form any part of the arch proper and all of the stresses developed in the arch are transmitted directly to the abutments H without passing through said blocks J, the function of which is to form a heat insulation for the metallic members. Furthermore, the stresses of the arch are not transmitted through the twyer members M and as a consequence these members may at any time be removed and replaced without affecting the arch.

In the continued use of the furnace the twyer members M will occasionally burn out, and whenever this occurs they may be removed and replaced without disturbing the arch abutment. Thus it is only necessary to remove the key R which locks any particular twyer member in position, after which it may be adjusted laterally to disengage the hooks P and drawn out of engagement with the sockets Q. A new section may then be engaged and locked by the key.

The construction of the member A with the flanges C and extensions H is such as to form a rigid arch abutment and at the same time one in which the metallic parts are thoroughly protected from the heat of the furnace chamber.

What I claim as my invention is:

40 1. In a furnace, the combination with a refractory arch, of a fuel magazine having a feed opening into the furnace chamber, the inner wall of said magazine being provided with means projecting therefrom forming arch abutments above said feed opening, and independent heat protecting members for said abutments arranged below the same and supported wholly thereby.

2. In a furnace, the combination with a refractory arch, of a fuel magazine having a feed opening into the furnace chamber, the inner wall of said magazine being provided with a series of vertical flanges projecting therefrom and forming arch abutments, and heat protecting members for said abutments arranged between said flanges and suspended therefrom above said feed opening.

3. In a furnace, the combination of a refractory arch, of a fuel magazine having a feed opening at its lower end into the furnace chamber, an arch abutment integral with the wall of the magazine whereby the compression stresses are directly transmitted to said wall of the magazine, and a heat

insulating member above said feed opening suspended from said abutment and protecting the same.

4. In a furnace, the combination with a refractory arch and an abutment therefor, of a heat insulating member supported by said abutment for protecting the abutment, and a twyer member below said heat protecting member independently removably secured to a part integral with said arch abutment. 75

5. In a furnace, the combination with a refractory arch and an abutment therefor, of a heat protecting member for said abutment arranged beneath the same, and a metallic twyer member detachably secured to a part 80 connected with said abutment, said heat protecting member and twyer member being supported independently of each other.

6. In a furnace, the combination with a refractory arch, of a fuel magazine having 85 flanges, certain of which constitute an arch abutment, a heat protecting member for said abutment, and a metallic twyer member below said heat protecting member and detachably secured to flanges on the magazine 90 wall independently of said heat protecting member.

7. In a furnace, the combination with a refractory arch, of a fuel magazine having a longitudinally ribbed and transversely 95 flanged inner wall forming an arch abutment, a twyer member below said arch abutment, and having means for detachably supporting the same from said inner wall of the magazine, said twyer member comprising a plurality of over-lapping interengaging parts adapted to be detached one from the other and from said inner wall of the magazine by a relative sliding movement. 100

8. In a furnace, the combination with a refractory arch, of a magazine having an inner wall provided with an abutment for said arch, a twyer member adapted to underlie said abutment having upwardly extending hooks, there being sockets formed on said inner wall of the magazine with which said hooks are detachably engaged, and a heat protecting member interposed between the twyer member and the arch abutment and supported by the latter. 110

9. In a furnace, the combination with a refractory arch, of a fuel magazine having a member forming the inner wall thereof, and an arch abutment, heat protecting members for the abutment, supported by and maintained in place by the abutment, a series of twyer members having laterally extending suspension hooks independently detachably engaging said inner wall member, and a locking member interposed between adjacent sides of the twyer members. 120

10. In a furnace, the combination with an arch abutment, and an arch supported thereby, of an independent removable heat protecting part comprising sections detachably 130

- connected directly to, and maintained in position by, the arch abutment, said detachable connection forming means to positively maintain the sections against accidental separation.
- 5 11. In a furnace, the combination with an upright wall having laterally extending flanges forming an arch seat or abutment, an arch supported by said abutment, a series of removable heat protecting members underlying said flanges, and projecting parts on certain of said flanges to engage the heat protecting members for supporting the same vertically.
- 10 12. In a furnace, the combination of an upright wall having laterally projecting flanges forming seats or abutments, an arch supported by said abutments, a removable heat protecting member underlying said abutments, and a plurality of independently removable metallic plate members supported by said wall and underlying the heat protecting members, and said supporting means permitting independent removal of any 25 plate of the series without disturbing adjacent plates of the series.
13. In a furnace, the combination with a refractory arch, of a fuel magazine having a feed opening into the furnace chamber, the inner wall of said magazine having a part to engage and form an abutment or seat for the end wall of the arch, and heat protecting members engaging over the under surface of said abutment and secured in place against accidental vertical separation by a part integral with the abutment.
- 30 14. In a furnace, the combination of a refractory arch, of a fuel magazine having a feed opening into the furnace chamber, the inner wall of said magazine having flanges extending vertically at an incline forming arch abutments or seats, and also having laterally extending flanges, a series of detachable protecting members having receiving 35 pockets to engage said lateral flanges, said members underlying the abutments and said lateral flanges, the connection between said lateral flanges and pockets maintaining the protecting members against downward separation.
- 40 15. In a furnace, the combination of a refractory arch, of a fuel magazine having a feed opening into the furnace chamber, the inner wall of said magazine having flanges extending vertically at an incline forming arch abutments or seats, and also having laterally extending flanges, a series of detachable protecting members having receiving 45 pockets to engage said lateral flanges, said members underlying the abutments and said lateral flanges, and a plurality of independently removable plates supported from said inner wall of the magazine and underlying the heat protecting members.
- 50 16. In a furnace, the combination of a refractory arch, of a fuel magazine having a feed opening into the furnace chamber, means projecting inwardly from said inner wall forming an arch abutment or seat, a series of abutting independently detachable 55 metallic plates supported from said inner wall and projecting inwardly below the abutments, and heat protecting means interposed between said plates and said abutments.
17. In a furnace, the combination of a refractory arch, of a fuel magazine having a feed opening into the furnace chamber, means projecting inwardly from said inner wall forming an arch abutment or seat, a series of over-lapping interengaging independently removable plates supported from said inner wall and projecting inwardly below the abutments, and heat protecting means 60 interposed between said plates and said abutments, said heat protecting means comprising a plurality of detachable sections.
18. In a furnace, the combination of an arch, a fuel magazine having a feed opening into the furnace chamber, means projecting from the inner wall of the furnace to form an arch seat, and heat protecting means for the arch seat comprising a plurality of independent blocks having end grooves, and lateral projections on said inner wall to engage within said grooves to support the blocks in position.
19. In a furnace, the combination of an arch, a fuel magazine having a feed opening into the furnace chamber, means projecting from the inner wall of the furnace to form an arch seat, heat protecting means for the arch seat comprising a plurality of independent blocks having end grooves, and lateral projections on said inner wall to engage within said grooves to support the blocks in position, and said blocks having end projections below said grooves, whereby the respective blocks abut and form a complete shield for the arch seat.
20. In a furnace, the combination with a refractory arch, of a fuel magazine having a feed opening into the furnace, the inner wall of said magazine having an inward projection adapted to engage and form an abutment or seat for the end wall of the arch, heat protecting members engaging over the under surface of said abutment, and an auxiliary projection integral with said abutment and inner wall of the magazine to engage 115 said heat protecting members so as to detachably maintain the same in place.
21. In a furnace, the combination with a refractory arch, of a fuel magazine having a feed opening into the furnace, the inner wall of said magazine having an inward projection adapted to engage and form an abutment or seat for the end wall of the arch, heat protecting members engaging over the under surface of said abutment, an auxiliary 120 projection integral with said abutment and inner wall of the magazine to engage 125 said heat protecting members so as to detachably maintain the same in place.
22. In a furnace, the combination with a refractory arch, of a fuel magazine having a feed opening into the furnace, the inner wall of said magazine having an inward projection adapted to engage and form an abutment or seat for the end wall of the arch, heat protecting members engaging over the under surface of said abutment, an auxiliary 130 projection integral with said abutment and inner wall of the magazine to engage said heat protecting members so as to detachably maintain the same in place.

projection integral with said abutment and inner wall of the magazine to engage said heat protecting members so as to detachably maintain the same in place, and metallic ⁵ twyer members adapted to underlie said protecting members and having upward projections to engage the under surface of the protecting members, means for detachably supporting said twyer members from the ¹⁰ inner wall of said magazine, and said twyer

members having overlapping portions, and adapted to be moved laterally whereby the respective twyer members are released from one another and from said inner wall.

In testimony whereof I affix my signature ¹⁵ in presence of two witnesses.

EDWIN FITTS.
